SHOE

John L. Cobb, Chicago, Ill., assignor of one-half
to Salem N. Baskin, Chicago, Ill.

Application November 25, 1936, Serial No. 112,813

3 Claims. (Cl. 36—68)

My invention relates to shoes and more particularly to the counters in the heel portions thereof, and my main object is to provide a counter which provides permanent comfort in cases 5 where the cuboidal formation of the weight-bearing arch is pronounced or abnormally projected.

A further object of the invention is to provide a counter which allows the top of the shoe to fit closely and neatly about the heel, despite the 10 presence of a cuboidal projection in the latter.

Another object of the invention is to so design the novel counter as to relieve the outer side of the shoe from undue wear as a result of pressure by a projecting cuboidal formation.

15 An additional object of the invention is to form the novel counter with an extension which is attachable to the waist of the shoe for purposes of reinforcement.

An important object of the invention is to design 20 the novel counter along lines of simplicity and compactness, whereby to be unnoticeable and adaptable to shoes of any style or design.

With the above objects in view, and any others which may suggest themselves from the description 25 to follow, a better understanding of the invention may be had by reference to the accompanying drawing, in which—

Fig. 1 is a perspective view of a shoe showing the novel counter by means of dotted lines;

30 Fig. 2 is a similar view, with the covering broken away to expose the main portion of the counter;

Fig. 3 is a cross-section of the counter in the region of the heel; and

35 Fig. 4 is a perspective view of the counter.

In the highly developed art of shoe making and styling, it is of the utmost importance to combine comfort and neatness of fit with styles of the day. This is often difficult where the foot has a pronounced cuboidal formation on the outer side of the heel, such formation not only causing discomfort when the shoe is tried on or worn, but also inducing the top or edge of the shoe to keep or bulge away from the foot. This imparts an 45 unsightly and loose appearance to the shoe and the impression that it does not fit the foot. Also, when a shoe so fitted is worn, the pressure of the cuboidal protuberance causes friction and undue wear in the outer wall of the shoe. I have therefore devised the improved counter with means to eliminate the above deficiencies and accomplish the objects outlined above.

In accordance with the foregoing, specific reference to the drawing indicates a typical low 50 shoe at 10, although the novel counter is equally

applicable to a high shoe, boot or any other type which encases the heel of the wearer.

The shoe counter, insofar as its rear portion 11 and its base 12 are concerned, is of conventional design. The forward portion, however, has the 5 wall 13 corresponding to the outer side of the shoe recessed with an opening 14, which is arch-shaped and extends from an approximately medial height to the bottom of the counter, continuing across the base flange 12. The latter is thus 10 divided by the opening to define the rear section and a frontal section 12a.

The recessed counter wall 13 is extended from its frontal, sloped edge 13a with a strip 15 which is at a height corresponding to the waist of the 15 shoe.

In the application of the novel counter, it is 20 encased between the shoe lining 16 and the outer covering 17 in the conventional manner, the base being secured between the welt 18 and the insole 19. The extended strip 15 is secured by the usual stitching in the lacing flap or instep, and the counter thus becomes the foundation and stiffening element of the shoe superstructure.

It is evident that the opening 14 rising from 25 the base in the outer counter wall, and located slightly forward of the wearer's heel, is at a point opposite the cuboidal region. In case the latter is pronounced or prominent, it will fill out the side of the shoe without encountering the resistance of the hard and unyielding counter wall, making the shoe comfortable. At the same time, the upper part of the shoe wall lies close to the 30 foot, makes a neat fit and retains its normal position as prescribed by the particular size, shape 35 and style of the shoe. As the outer covering and lining form immediate closures for the sides of the opening 14, no deformation of the shoe is apparent, and the same presents the appearance of other shoes of the same size and style. In 40 fact, all shoes could be made with the improved counter, to avoid carrying a special line for feet formed with cuboidal prominence, since the fit and appearance are clearly suitable for feet of 45 normal form.

The extended strip 15 is a stiffener and reinforcing element for the waist of the shoe, and serves to check the collapse of the same. Being a part of the counter, the strip has a solid source 50 and support; also, its integral construction with the counter eliminates special fastening means and other complications.

It will be evident from the above description 55 that I have improved the conventional shoe counter with means of extreme simplicity to pro-

vide relief for cuboidal pressure, comfort during wear, a close fit, freedom from undue wear, and a neat external appearance. Obviously, the simplicity of the counter renders its manufacture nearly or entirely as economical as the standard article, while imparting highly desirable values to a shoe so improved.

While I have described the invention along specific lines, the same is susceptible of various changes and refinements, and I consider all such changes and refinements as coming within the scope and spirit of the appended claims.

I claim:—

1. In a shoe, a relatively stiff counter therefor, the outer side wall of said counter being re-

cessed to provide an opening therein extending at both sides of the breast line, said opening being positioned to permit the extension of the outer cuboidal bone of a foot therethrough without distorting the counter.

5

2. The structure of claim 1, and the upper edge of said outer wall of said counter having an extension formed thereon, said extension extending into the lacing flap of said shoe.

10

3. The structure of claim 1, the upper edge of said outer wall of said counter having an integral strip formed thereon, said strip extending into the lacing flap of said shoe.

10
